A. R. Wallace.

UNITED STATES PATENT OFFICE.

ANNE R. WALLACE, OF TYRONE, PENNSYLVANIA.

PROTECTIVE LIGHT ARMOR.

1,418,995.

Specification of Letters Patent. Patented June 6, 1922.

Application filed August 11, 1921. Serial No. 491,619.

To all whom it may concern:

Be it known that I, ANNE ROGERS WALLACE, a citizen of the United States, residing at Tyrone, in the county of Blair and State of Pennsylvania, have invented a new and useful protective light armor for protecting the occupants of aeroplanes, dirigible balloons, the fighting tops of warships, and similar exposed positions from rifle, machine-gun, or similar small-caliber fire.

The essential feature of the invention lies in its employment of loosely hanging and overlapping strips of a flexible chain mail, or scale mail armor; composed of units of hardened steel, steel alloy, or any such suitable tough resistant metal.

The loosely hanging strips of the flexible mail are each about nine inches wide; and say thirty inches long hanging loosely from a supporting bar or bars and so arranged in a double, or a triple, etc., row around the area to be protected; that the openings between any two adjacent strips in a given row falls immediately in the middle of a hanging strip in the companion row, before, or behind, so that the said loosely hanging strips overlap, as stated, there being a space of say an inch and a half or two inches between the inner and the outer rows of said hanging strips.

Besides the top supporting bar or bars, if the cock-pit of an aeroplane is being protected, since this must be able to "loop the loop"; the two or more rows of loosely hanging flexible mail strips should also be secured, by flexible lacings of spiral spring or similar elastic lacings, to bottom bar or bars, which bottom bar or bars will become the supporting bar or bars; when the aeroplane is upside-down.

While in the case of the loosely hanging and flexible mail strips protecting the aeroplane's gasoline tank; engines, bottom of the cockpit, and similar points; the two or more rows of strips may run in different directions; say cross-ways.

The accompanying drawing shows a sec-

tion of such protective light armor for the cock-pit of an aeroplane composed of portions of two overlapping layers of strips of flexible chain mail. The front set of hanging strips; namely 9, 10, and 11, hangs by elastic lacings from the top supporting bar 1, 2, and fastened, in like manner elastically, to the bottom bar 5, 6, which bottom bar becomes the supporting bar, when the aeroplane is upside-down.

Similarly, the rear supporting bar has the rear row of loosely hanging mail strips, 12, 13, 14, and 15, hanging from it and these strips 12, 13, 14, and 15, are similarly elastically laced to a bottom bar 7, 8; so that this will act as a supporting bar when the aeroplane is inverted.

The openings between the front row of strips; between 9 and 10; and between 10 and 11; fall directly in front of the mid points of the hanging strips 13, and 14, and conversely the openings between 12 and 13; between 13 and 14; and between 14 and 15 fall behind the mid-points of strips 9, 10, and 11.

The essential protective principle involved here is that employed by the red Indian warrior; when he shielded himself from rifle or musket balls by catching them in his blanket, loosely held before him, which idea is also embodied in the Japanese Samurai armor; wherein the fluttering silk streamers were designed to catch and baffle the enemy's flying arrows.

I claim—

A protective light armor comprising spaced series of adjacent strips of loosely hanging flexible mail composed of tough resistant metal, the meeting edges of the strips of one series being arranged in staggered relation to the meeting edges of the strips of an adjacent series.

ANNE R. WALLACE.
